UNITED STATES PATENT OFFICE.

LAWRENCE M. PERSONS, OF QUINCY, ILLINOIS, ASSIGNOR, BY MESNE ASSIGNMENTS, TO H. B. SHERMAN MANUFACTURING CO., OF BATTLE CREEK, MICHIGAN. A CORPORATION OF MICHIGAN.

MOTOR STARTING SWITCH.

Application filed October 7, 1919. Serial No. 328,955.

To all whom it may concern:

Be it known that I, LAWRENCE M. PERSONS, a citizen of the United States, residing at Quincy, in the county of Adams and

5 State of Illinois, have invented a certain new and useful Improvement in Motor Starting Switches, of which the following is a specification.

My invention relates to a starting switch 10 for electric motors and has for its object to provide a starting switch for split phase motors which is automatically cut out of action by the acceleration of the rotation of the rotor. Other objects will appear from 15 time to time in the specification.

My invention is illustrated more or less diagrammatically in the accompanying drawings wherein:

Figure 1 is an elevation of my motor and 20 starter with parts cut away;

Figure 2 is an elevation of the starter and adjacent parts.

Figure 3 is an end view of my motor 25 starter.

Like parts are indicated by like figures and letters throughout.

A is a motor casing with a base A¹, enclosing the usual field A² of a split phase motor and having any suitable plug connection A³, on the removable end section or 30 blade A⁴ of the casing. Mounted on the inside of the same casing are the stationary contacts A⁵ A⁶, illustrated as opposed copper strips.

B is a rotor of the usual type mounted on a shaft B¹ and provided with lubricating means B² B³. Rotatable on the rotor shaft and movable therewith, is the sleeve C, which has at either end, up-turned rims 35 C¹ C¹.

From the end and rim farthest from the contacts A⁵, project the opposed arms C² C², inclined toward the contacts, and terminating in enlarged ends C³ C³. Loosely mounted on the sleeve, is an insulated ring 40 normally composed of a conductive rim or facing C⁴ backed by a non-conductive backing and inner periphery C⁵. The disposition of the two parts is such that the conductive rim or face, although bridging the two contacts A⁵, is thoroughly insulated from the

sleeve and other working parts. A spring C⁶ coiled about the sleeve, presses the ring forward along the sleeve and against the contacts.

Mounted on the rotor is the yoke D with 55 eccentric bearings or hinges D¹. Mounted therein are the centrifugal weights D² D² in the form of curved blades slotted as at D³ to engage the arms C². Springs D⁴ D⁴ tend to draw the weights or blades inwardly 60 about the rotor axis. The rotation of the rotor throws the curved blades or weights D² D² eccentrically outward and moves the sleeve C and the ring C⁴ axially away from the fixed contacts, by the engagement of the 65 curved arms C² by the slots D³. The enlarged ends of the arms limit the centrifugal excursion of the weights during motor rotation. Although I have illustrated a working mechanism, it is obvious that many 70 changes of shape and disposition of parts could be made without departing from the spirit of my invention, and I wish therefore, that my drawings and description may be regarded as in a sense, diagrammatic. 75

The use and operation of my invention are as follows:

My starting device is adapted for use with motors where a separate starting current or connection is used and more particularly, is useful with split phase alternating current motors. In this class of motor, it is desirable to start the motor by a connection which is broken before the motor approaches full speed. When the rotor is at 85 rest, the insulated ring forms a starting connection by its contact with the two stationary contacts against which it normally rests. When the current is thrown on, it bridges the two contacts, and starts the motor. The 90 ring is forced against the contacts by the coiled spring compressed between it and the opposite raised end of the sleeve on which it is mounted. The sleeve itself is normally forced in the direction of the contacts by 95 the compression of the centrifugal weights, on the inclined arms of the sleeve. When the starting switch is thrown, the rotor, of course, begins rotation and rotates with it the collar or yoke carrying the switch gov- 100

erning weights. When rotation approaches high speed, centrifugal force is enough to oppose the weight compressing springs and to carry the weights out from their normal position about the rotor axis. Since they are slotted to engage the arms on the ring carrying sleeve and since those arms are inclined toward the ring and terminals engaged thereby, the outward movement of the weights withdraws the sleeve and ring and almost instantaneously breaks the starting current. The starting mechanism operates with the rotor. When rotation ceases the weights are actuated by their springs, the sleeve is forced forward, and the ring bridges the contacts. It reaches the contacts before it has ceased rotation and makes a partial revolution while in contact with them. This form of switch is extremely reliable because the ring makes a partial revolution on the stationary contacts after each revolution of the rotor and thus wipes them free from dust, grease, oxides or any other foreign matter which tends to accumulate thereon. Since the ring is rotatable on the sleeve on which it is mounted, it comes to rest before the rotor, and thus brings the wear of the contacting parts to a minimum, and insures a practically permanent close contact of ring and contacts. The thorough insulation of the ring with its large cross section of insulating material prevents grounding. The switch being inside of the rotor casing is protected from blows or pressure.

I claim:

1. In a starting switch for motors, a rotor, a plurality of starting circuit contacts, means for connecting said contacts when the motor is at rest, comprising an axially movable sleeve concentric with the rotor, a ring rotatably and axially movable thereon, and adapted to connect said contacts, yielding means mounted upon said sleeve adapted to hold said ring at the end of the sleeve adjacent said contacts, and centrifugal means rotated by the rotor for withdrawing said sleeve and ring from said contacts.
2. In a starting switch for motors, a rotor, a plurality of starting circuit contacts, means for connecting said contacts when the motor is at rest, comprising an axially movable sleeve concentric with the rotor, a ring rotatably and axially movable thereon, and adapted to connect said contacts, yielding means mounted upon said sleeve adapted to hold said ring at the end of the sleeve adjacent said contacts, and centrifugal means rotated by the rotor for withdrawing said sleeve and ring from said contacts, comprising a pair of opposed hinged centrifugal arms, and yielding means normally drawing their ends toward the rotor axis.

3. In a starting switch for motors, a rotor, a plurality of starting circuit contacts, means for bridging said contacts comprising a ring, means for holding it normally against the contacts, and means adapted during rotation of the rotor to withdraw the ring from the contacts, comprising arms in connection with the ring inclined toward the contacts, and centrifugal means pivoted to the rotor adapted slidably to engage said arms.

4. In a starting switch for motors, a rotor, a plurality of starting circuit contacts, means for bridging said contacts comprising a sleeve, an insulated ring rotatable thereon, means for normally holding said ring against the contacts, means adapted during rotation of the rotor to withdraw the ring from the contacts, comprising arms on the sleeve inclined toward the contacts, and centrifugal means pivoted to the rotor adapted slidably to engage said arms.

5. In a starting switch for motors, a rotor, a plurality of starting circuit contacts, means for connecting said contacts comprising a sleeve, an insulated ring rotatable thereon, yielding means normally forcing the ring against the contacts, means adapted, during rotation of the rotor, to withdraw the ring from the contacts, comprising arms on the sleeve inclined toward the contacts, centrifugal weights mounted on the rotor and slotted to engage the arms.

6. In a starting switch for motors, a rotor, a plurality of starting circuit contacts, means for connecting said contacts comprising a sleeve, an insulated ring rotatable thereon, yielding means normally forcing the ring against the contacts, means adapted, during rotation of the rotor, to withdraw the ring from the contacts, comprising arms on the sleeve inclined toward the contacts, weights mounted on the rotor and slotted to engage the arms, together with yielding means adapted during slow rotation or non-rotation of the rotor, to draw the weights toward the axis of rotation of the rotor.

7. In a starting switch for motors, a plurality of starting circuit contacts, a rotor and shaft, means for connecting said contacts when the motor is at rest, comprising a sleeve rotatable on the rotor shaft and movable therealong, an insulated ring movable on the sleeve, yielding means for holding the ring against the contacts when the rotor is at rest, and centrifugal means for withdrawing the sleeve and ring along the rotor shaft during rotation comprising a pair of opposed centrifugal weights adapted to rotate in a plane perpendicular to the axis of the shaft.

8. In a starting switch for motors, a plurality of starting circuit contacts, a rotor and shaft, means for connecting said contacts when the motor is at rest, comprising a

sleeve on the rotor shaft and movable therealong, an insulated ring axially movable and rotatable on the sleeve and yielding means mounted upon said sleeve and movable with it, adapted normally to hold said ring at the end of the sleeve adjacent said starting contacts.

9. In a starting switch for motors, a rotor, a plurality of starting circuit contacts, means for connecting said contacts comprising a sleeve, an insulated ring rotatable thereon, yielding means normally forcing the ring against the contacts, means adapted, during rotation of the rotor, to withdraw the ring from the contacts, comprising arms on the sleeve inclined toward the contacts, weights pivoted on the rotor and slotted to engage the arms, and means at the ends of the arms adapted for limiting the centrifugal excursion of the weights.

10. In a starting switch for motors, a rotor, a plurality of starting circuit contacts, means for connecting said contacts when the motor is at rest, comprising a ring concentric with the rotor and rotatable in relation thereto, yielding means for forcing said ring against said contacts, and means adapted to withdraw said ring and said yielding means axially away from said contacts, in response to a pre-determined speed of rotation of the rotor, comprising centrifugal weights pivoted at points spaced from the axis of rotation of the rotor and adapted to rotate in a plane perpendicular thereto.

11. In a starting switch for motors, a plurality of starting contacts, a rotor and means for connecting said contacts when the rotor is at rest, comprising a sleeve rotatable on the rotor shaft and movable therealong, an insulated ring axially and rotatably movable on the sleeve, inclined members in connection with said sleeve, centrifugal elements in contact with said inclined members, and adapted to centrifugally move in a plane perpendicular to the axis of the rotor.

12. In a starting switch for motors, a plurality of starting contacts, a rotor and means for connecting said contacts when the rotor is at rest, comprising a sleeve rotatable on the rotor shaft and movable therealong, an insulated ring axially and rotatably movable on the sleeve, inclined members in connection with said sleeve, slotted centrifugal elements in contact with said inclined members, and adapted to centrifugally move in a plane perpendicular to the axis of the rotor, said inclined elements adapted to pass through said slotted members.

13. In a starting switch for motors, a plurality of starting circuit contacts, a rotor and shaft and means for connecting said contacts when the rotor is at rest comprising a sleeve rotatable on the rotor shaft and movable therealong and a contact bridging element in contact therealong, inclined arms force in a plane transverse to their axis of

outwardly projecting from said sleeve, slotted centrifugal elements adapted to engage said arms by said slots and adapted to be moved outwardly in a plane perpendicular to the axis of rotation of the rotor.

70

14. A motor starting switch comprising a motor shaft, centrifugally swinging weights connected to rotate with said shaft, a pair of fixed contacts, a ring slidably mounted on said shaft and having radially extending arms, and a contact operatively connected with said swinging weights by said ring and arms and arranged to be moved by said ring into and out of engagement with said fixed contacts.

75

80

15. A motor starting switch comprising a motor shaft, a pair of weights mounted for swinging toward and away from said shaft, a contact mounted for sliding longitudinally with respect to the shaft, a fixed contact, and a connection between said swinging weights and said first-mentioned contact for moving the latter into and out of engagement with the fixed contact, said connection comprising a ring slidably mounted on said shaft and having radially extending arms loosely engaging said weights.

85

16. A starting switch comprising a motor shaft; a weight mounted for swinging toward and away from said shaft; a ring around said shaft and slidable thereon; an arm on said ring engaging said weight; a fixed contact; and a contact carried by said ring and movable thereby into engagement with said fixed contact.

90

95

17. In a motor, a fixed contact, a rotating contact slidable to and from said fixed contact, a radially extending member connected to said rotating contact and inclined longitudinally of the axis of the latter's rotation, a weighted arm rotatable with said rotating contact, pivoted to swing transversely of the axis of rotation at a predetermined rotating speed, and positioned to engage said member, as it swings, to move the latter and said rotating contact along the axis of rotation.

105

18. In a centrifugal starting switch radially movable weights adapted to be attached to a rotatable part, a member movable axially of said part, and interengageable members carried by the weight and said axially movable member whereby when the weight is moved outwardly the member is moved inwardly and vice versa; a rotatable contact carried on said axially movable member, and relatively fixed contact members adapted to be engaged by the rotatable contact when the parts are in normal position.

110

115

19. In an automatic cut-out for electric motors, starting winding contacts, a contact ring co-operating therewith, cam track members engaging said ring and levers rotated by the motor and operated by centrifugal force in a plane transverse to their axis of

120

rotation, for engaging and moving said cam track members and said ring away from said contacts.

20. In a centrifugal starting switch, a rotatable member, movable weights on said member adapted to be moved outwardly by centrifugal force, a contact carrier movable axially of said member, and engaging arms on the contact carrier and weights whereby 10 the contact carrier is caused to move axially

by and in proportion to the radial movement of the weights.

In testimony whereof, I affix my signature in the presence of two witnesses this 29th day of September, 1919.
